UNITED STATES PATENT OFFICE

ALEXANDER WEINER, OF PROVIDENCE, RHODE ISLAND

DESIGN FOR A NECK CHAIN

Application filed September 6, 1929. Serial No. 32,677. Term of patent 14 years.

To all whom it may concern:

Be it known that I, ALEXANDER WEINER, a citizen of the United States, residing at Providence, in the county of Providence and State of Rhode Island, have invented a new, original, and ornamental Design for a Neck Chain, of which the following is a specification.

In the accompanying drawings which form a part of this specification the figure is a front view of a neck chain embodying my new design.

I claim:

The ornamental design for a neck chain, as shown.

ALEXANDER WEINER.
